(57) **CLAIM**

The ornamental design for a telemetry module for a therapeutic medical device, as shown and described.

DESCRIPTION

FIG. 1 is a front perspective view of the telemetry module for a therapeutic medical device;

FIG. 2 is a front view thereof;

FIG. 3 is a rear perspective view thereof;

FIG. 4 is a top view thereof;

FIG. 5 is a left side view thereof;

FIG. 6 is a right side view thereof; and,

FIG. 7 is a bottom view thereof.

The broken lines in the figures depict portions of the telemetry module for a therapeutic medical device and form no part of the claimed design.
